BOTTLE HANDLING MACHINE

John Cattener, Jamaica, and George Ohm,
Astoria, N. Y., assignors to Edward Ermold Co.,
New York, N. Y., a corporation of New York

Application March 26, 1941, Serial No. 385,240

4 Claims. (Cl. 214—1)

This invention relates to improvements in packaging machines. More specifically, the present invention embodies improvements in applicants' Bottle packaging machine, Patent No. 2,277,688, dated March 31, 1942, which described the loading of bottles, jars and similar containers into boxes or cases or crates, having compartments to receive said bottles or similar containers.

The present invention provides an improved means of gripping the neck of the bottles, etc., previous to the loading operation by such a machine, offering thereby a departure in the art, considerable reduction of motion of its operative parts and a convenient adjustment for a wide range in height and diameter of bottles or containers to be handled.

The invention consists of a gripping device system for gripping the neck of bottles, or similar containers, to grip a single bottle, a row of bottles, two rows of bottles, three rows of bottles, etc. The invention will be fully described hereinafter and embodiments shown in the drawings which illustrate a convenient arrangement of the novel features entering into the invention, it being understood that it is permissible to make slight changes of details to suit manufacturing requirements without departing from the spirit of the present invention defined herein and the scope of the appended claims.

The accompanying drawings are an illustration of the embodiment in a preferred way and the relative position of the different features and the scope in relation to the features described in applicants' Patent #2,277,688.

Fig. 1 shows a front view of the improved machine with only two double gripping devices shown, although any number of these may be used, so as to suit the number of bottles in the longer, or lengthwise rows of the case to be loaded;

Fig. 2 shows a top view taken at about the level of line 2—2 of Fig. 1, the position of the bottle slider being in the proper relation to the position of the gripper jaws of Fig. 1;

Fig. 3 is a side elevation along a section taken on line 3—3 of Fig. 1;

Fig. 4 shows a partial side section taken at line 4—4 of Fig. 2, with some of the parts omitted for clearness;

Fig. 5 shows in detail the mechanism for and the gripping device in its "locked" position;

Fig. 6 shows a section of said mechanism and the gripping device taken on line 6—6 of Fig. 5 at its "release" position;

Fig. 7 shows a detail section of the gripper

jaws taken on line 7—7 of Fig. 6, and their relative position in respect to the key and the bottle just before "locking" the neck of the bottle;

Fig. 8 is an enlarged view of the gripper carrying yoke as seen from line 8—8 of Fig. 6;

Fig. 9 shows a top view of the ends of the gripper jaws taken from line 9—9 of Fig. 5;

Fig. 10 is an enlarged view taken at line 10—10 of Fig. 6 and shows the assembly of the grippers at that point; and

Fig. 11 is a top view of the gripper guiding and operating parts, hereafter called "interrupter carriage" taken at different levels, approximately on line 11—11 of Fig. 1.

Referring to the drawings, the machine is contained in a frame work composed of walls 1 and 2 and cross members 3 and 4. Two large brackets of convenient shape support most of the mechanism on and about the bottle level, being indicated on the left-hand frame 1 by 5, and on the right-hand frame 2 by 6. As seen in Fig. 4, cross member 7 connects 5 and 6 and serves also as a guide into which a suitable projection 8a of a trap floor 8 is slidably mounted and covered with a cover 9.

As seen in Fig. 2, cam shaft 10 rotates in its bearing 11 and 12 fastened in the wall frames 1 and 2, respectively, and carries a number of cams of which 13 at the left and 14 at the right of equal path impart the necessary motion to the gripper carriage, through rollers 15, followers 16 and levers 17 which rock on shaft 13 fast in frames 1 and 2. To counteract the weights of the gripper carriage parts and the full bottles being handled, a counterweight 19 is bolted to the rear ends of the levers 17.

As seen in Figs. 1, 3 and 11, the levers 17 are connected through links 20 to a cross member 21, the two ends of which are guided by the flanged body of a rack 22 fast on frame 1, and rack 23 fast on frame 2. On one end of the cross member 21, one pinion 24 runs on the pin 25 fast on bearings 26, which bearings are part of cross member 21 and engage rack 22, and diametrically opposite engage rack 27; at the other end of 21, another pinion 24 similarly mounted engages rack 23 and diametrically opposite engages rack 28. Guides 29 and 30 fastened on the cross member 21 together with covers 31 present two vertical guides into which racks 27 and 28 slide during their vertical movement. The upper end of the rack 27 through a bracket 32 and adjusting screw connects with one end of a gripper carrier 36, and likewise the rack 28 through bracket 34 and adjusting screw 35, connects with

the other end of the gripper carrier 36. As best shown in Fig. 1, cross member 21 through adjusting screw 37 connects with one end of the interrupter carrier 38 and through adjusting screw 39 connects with the other end of the interrupter carrier 38.

It will be seen from Figs. 1 and 5 that the interrupter carrier 38 being directly connected with the pinion carrying cross member 21, will travel up and down a distance equal to the motion imparted to 21 by cams 13 and 14, follower 16, levers 17, etc. Again the gripping carrier 36 being directly connected to the free racks 27 and 28 will travel up and down at the same time and in the same direction as interrupter carrier 38, but at a speed equal to twice the speed of interrupter carrier 38. The distance between the gripper and interrupter carriers will decrease during their downward travel and correspondingly increase during their upward travel. The difference in speed of said two carriers is here utilized to operate the gripper jaws as follows:

Gripper carrier 36 (Fig. 1) is more or less a cast frame with a long slot in which are slidably mounted blocks 40 which can be shifted by means of set screw 41 in slot 42 of cover 43 to match perpendicularly the distance between the center of adjacent bottles in the row or rows being assembled on trap floor 8 below. A threaded tube 44 is inserted into each block 40 and fastened rigidly to it by nuts 45 at the upper end while at its lower end also threaded is fastened frame 46 carrying blocks 47 into which are inserted and to which are fastened by means of nuts 49, tubes 48, in the same fashion as tubes 44 are fastened to blocks 40 of gripper carrier 36. Also in the same fashion as blocks 40, blocks 47 with tubes 48 can be shifted by means of set screw 50 in slot 51 of frame 46. It is here pointed out that with the blocks 40, the desired adjustment is obtained to match the distance between the center of the bottles in the row or rows, while with the blocks 47 the desired adjustment is obtained to match the distance between the center of the rows of bottles being assembled to be loaded. To the lower ends of tubes 48 are fastened blocks 52 to which on pins 53 are hinged gripper jaws 54 (Figs. 5 and 7). Tension spring 57 of which each end is attached to one gripper jaw 54 urges continuously the two jaws to lock, but their locking and releasing operations depend entirely on the position on which rollers 55, carried also by jaws 56, roll on the operative face of key 72.

So far a direct and rigid connection has been shown to exist all the way from gripper carrier 36 down to gripper jaws 54 with springs 57 and rollers 55.

As seen in Figs. 5, 6 and 11, inside of tube 44 slides a round bar 58 which rigidly connects with collar 59 around tube 44 by means of screw 60 at a point near its upper end, and at its lower end it connects much in the same fashion with threaded collar 61 by means of screw 62.

The interrupter carrier 38, similar in construction to gripper carrier 36, carries blocks 63 which also can be shifted by means of set screws 64 in slots 65 of cover 66 to match the blocks 40 above. Tube 44 is free to slide in blocks 63 of carrier 38, in collar 59 and also in threaded collar 61. Screws 60 and 62 on bar 58 are free to run in the wall of tube 44 along slot 67 above blocks 63 and in slot 68 below threaded collar 61, respectively.

As shown in Figs. 6, 8 and 11, between the

shoulder of the threaded collar 61 and nut 69 there is a loosely locked yoke 70 at each end of which is inserted a round bar 71 which slides in tube 48 and which at its lower end carries key 72 to operate the gripper jaws 54. It will be observed in Fig. 7, that key 72 presents to each roller 55 to roll on, two vertically straight faces 72a and 72c and one sloped one in between 72b.

10 The operation of the gripper jaws is as follows:

In their upward travel at the higher rate of speed, racks 27 and 28 (Fig. 1) will take along the gripper carrier 36 with tubes 44, 48, bars 53, 71, jaws 54, keys 72, etc., to a point, near the end of their upward travel at which the top of nut 68 will hit the bottom of block 63 in carrier 38 which travels at low speed. This will cause the rate of speed at which bars 58, 71, screws 60 and 62, collars 61, 59, keys 72, etc., travel (Fig. 8) to be retarded while jaws 54, tubes 48, 44 and all parts connected therewith continue at the same high rate of speed for the rest of the upward travel. Roller 55 at this time will have so run off face 72a down slope 72b to face 72c and by action of springs 57, the jaws 54 will close and lock the neck of bottle B (Fig. 7). At this time the upward travel of the gripping device will have ceased, trap floor 8 will shift and with it the bottle supporting strips 76 from under the bottles and the gripping devices with the bottles locked will start their downward travel toward case C on the case conveyor floor below.

In their downward travel again, all parts and bottles will travel at the high rate of speed with

racks 27 and 28 until the bottom of collars 59 will hit the top of blocks 63 in carrier 38 which travels at low speed (Fig. 6): this will again retard the speed of bars 58, 71, screws 60 and 62, collars 59 and 61 and key 72 while tubes 44, 48, jaws 54 and all parts connected therewith will continue at high speed for the rest of the downward travel, roller 55, will run off face 72c, up slope 72b to face 72a (Fig. 7), jaws will spread apart releasing bottle B into case C. Compression spring 73 in bars 71 (Fig. 1) act as shock absorbers for bottles B. Indicators 74 and 75 point to marks on guides 29 and racks 27 and 28, and indicate the different heights at which carriers 36 and 38 should be set in order to grip 50 and release at the proper time bottles of different heights.

It has been seen that the improvements hereinabove set forth consist of gripping device systems for gripping the neck of bottles or similar containers, to grip a single bottle, a row of bottles, two rows of bottles, three rows of bottles, etc.

Divisional applications Ser. No. 429,744 and Ser. No. 429,745, respectively, have been filed February 6, 1942.

60 From the foregoing it is believed that the construction and advantages of the invention may be readily understood by those skilled in the art without further description, it being borne in mind that numerous changes may be made in 65 the details disclosed without departing from the spirit of the invention as set out in the following claims.

What we claim is:

1. In a bottle packaging machine, a gripping device comprising a pair of vertically disposed jaws having their lower ends provided with bottle neck engaging flanges, a horizontally disposed link connecting the other ends of the jaws, means for raising and lowering the link at a predetermined speed of movement, means pivoting each

jaw to each end of the link, a follower on each jaw disposed between the ends of the jaws, one projecting towards the other, a spring below said followers pulling the jaws towards each other, a vertically movable cam disposed between the followers to open the free ends of the jaws against the action of the spring, means operatively connecting said cam with said raising and lowering means for movement of said jaws and cam in unison, and means interposed at a predetermined point in the path of movement of said cam to retard movement of said cam relative to said jaws whereby to effect movement of said cam relative to said followers.

2. In a bottle packaging machine, the combination of a pair of pivoted jaws movable respectively to bottle engaging and bottle releasing positions, spring means normally maintaining said jaws in bottle engaging position, cam means disposed between said jaws, supporting means for said jaws and cam means and movable vertically to raised and lowered positions to correspondingly raise and lower said jaws and cam means at a predetermined speed, means movable simultaneously with said supporting means but at a slower speed and arranged in the path of movement of said cam means to retard the speed of movement of the latter relative to said jaws at a predetermined point in the path of movement of the latter, and means cooperating with said cam means during movement of the latter at a speed less than that of said jaws to move said jaws from bottle engaging position to bottle releasing position against the action of said spring means during movement of said supporting means in one direction and to permit movement of said jaws from bottle releasing to bottle engaging position by said spring means during movement of said supporting means in the opposite direction.

3. In a bottle packaging machine, a gripping device comprising a pair of jaws having their lower ends provided with bottle neck engaging flanges, a link connecting the other end of the jaws, means for supporting the link, means pivoting each jaw to each end of the link, a follower on each jaw disposed between the ends of the jaws, one projecting towards the other, a spring below said followers pulling the jaws towards each other, a movable cam disposed between the followers to open the free ends of the jaws against the action of the spring, means for raising and lowering said jaws at a predetermined speed of movement, means operatively connecting said cam to said raising and lowering means for movement of said cam simultaneously with said jaws and in the same direction, and means operable to retard movement of said cam relative to said jaws at a predetermined point adjacent the raised and lowered positions of said jaws whereby to permit movement of the follower on each jaw relative to said cam.
4. In a bottle packaging machine, a gripping device having a pair of matched flanges in reverse each of substantially semi-circular shape to conform to the curvature of the neck of the bottle at its shortest diameter below the cap engaging bulb, and when closed against the neck only partially surrounding said neck and diametrically opposite to each other, cam means interposed between said flanges and adapted to move relative to the latter for movement of said flanges to gripping and releasing positions, and means for moving said flanges and cam means simultaneously and in the same direction but at different speeds relative to one another whereby to effect movement of said cam means relative to said flange.
